UNITED STATES PATENT OFFICE

FORREST C. GARRISON, OF EVANSTON, ILLINOIS, ASSIGNOR TO THE OSCAR C. RIXSON CO., OF CHICAGO, ILLINOIS, A CORPORATION OF ILLINOIS

TRANSOM WINDOW OPERATING MEANS

Application filed June 16, 1930. Serial No. 461,551.

This invention relates to supporting and swinging mechanism of transom windows or other similar casement structures.

The purposes of the invention are to provide structural improvements in transom operating means and mounting therefor, and to provide improvements in appearance and operation of such structures.

Figure 1 is a fragmentary front view of 10 a transom over a door showing a preferred location of a manually turnable knob by which transom-operating means is adjusted. Fig. 2 is a sectional detail on the line 2-2 of Fig. 1.

Fig. 3 is a side view of the transom-operating means, the part shown in section being taken on the line 3-3 of Fig. 1.

Fig. 4 is a sectional view partly broken away taken transversely through the transom, as indicated by the line 4-4 of Fig. 1.

Fig. 5 is a perspective detail of the transom-operating means.

Fig. 6 is a detail partly in section showing the mounting of a worm by means of which, 25 through a worm wheel and parallel links, the transom is adjusted around its hinges or pivots.

The transom operator herein disclosed is designed for mounting within a partition 30 post or door frame, in order to be out of view and require no change in the appearance of a door frame structure, except for the mounting of a small rotatable handle by which the transom is manipulated. It is generally common with transom operating 35 means, whether exposed to view or concealed within a partition post, to transmit motion to the transom, both by thrust and pull. In such cases, unless the operating bars or rods are of sufficient rigidity and there is a long span between bearings, the operating means 40 may not shift easily, due to a tendency to bend or buckle.

In the improved construction herein described, a light and easily manipulated mechanism is provided wherein parallel links are employed to shift the transom in both directions by a tension on one or the other of the links. A thrust action is avoided.

50 The invention is carried out by means of

a parallel link structure in which the links are shifted in opposite directions by means of a worm which is turned by a handle extending through the partition post and operates a worm wheel sector to which the 55 transom operating links are pivoted.

Figure 1 of the drawings shows a door 1 and transom window 2 mounted thereover in a frame structure, including the partition posts 3 and 4. The partition post 3 is hollow and receives the transom operator which includes a lower bent metal support and housing 5 for the worm gearing at the lower end of the transom operator and a supporting bearing 6 at the upper end of the transom operator, each of which is attached by the screws 7 and 8 to a vertical channel member 9.

The channel member 9 and channel member 10 form the partition post. These members carry clips 11 which are attached thereto by rivets 12 and are constructed to removably receive the metal moldings 13.

The transom 2 is pivotally mounted within the door frame structure by having attached to its outer side faces plates or arms 14 and 15 by means of screws 16 and 17, and which arms respectively carry trunnions 18, and a hollow shaft 19 passing through the bearing 6. Trunnion 18 is riveted to arm 14 and provides a pivotal support for one 75 side of the transom by extending into a bearing thimble 20 seated in an aperture 21 in the door and transom frame. The hollow shaft 19 is preferably rolled from flat stock and is provided at each end with projecting 80 lugs 22 which fit corresponding apertures in transom supporting arm 15 and a disk-shaped connecting lever 23 to which the transom operating links 24 and 25 are pivoted.

The shaft 19 is clamped between the arm 15 and link-connecting lever 23 by bolt 26 which is threaded into a central aperture 27 in lever 23. The disk-shaped lever 23 is provided with projecting ears 28 to which are riveted headed pins 29, passing through slots 30 in the upper ends of the links 24 and 25. A downward pull on either one of the links will, therefore, result in rotation of shaft 19 within its bearing 6 and a consequent adjustment of the transom because of the fixed 100

connection between the shaft 19 and the transom arm 15.

The links 24 and 25 extend downwardly from their pivotal connections with lever 23 to a worm wheel 31 near a transom-operating handle 32, the latter being at a convenient height for manual operation. The worm wheel 31 is rotatably mounted upon a pin 32, supported in apertures in the side of housing 5 and is spaced from the walls of the housing by the collars 33. Worm wheel 31 has ears 34 to which the links 24 and 25 are pivoted by the headed rivets 35. The worm wheel 31, including the ears 34 thereon, is a flat member having worm teeth 36 formed on the lower edge thereof. A worm 37, meshing with the wheel 31, is supported on its annular flanges 38 and 39 by a rivet 40 and bearing sleeve 41 respectively. The flange 39 has a squared socket 42 for receiving the square end of the handle stem 43. The handle stem passes through an opening in the molding 13 and is round in cross section where it passes through the bearing 44 attached to the molding 13. The handle 32 is prevented from moving endwise through the bearing 44 by a washer 45, forced on to the squared end of the handle stem.

When the transom operator is installed, the center of the shaft 19, around which the transom swings, and the center of the pin 32 for the worm wheel 31, are at such distance apart that the slots 30 at the upper ends of links 24 and 25 are below the pivot pins 29, Figure 3. Thus in the operation of the device, the turning of handle 32, in either direction, will result in a downward pull on one or the other of the links and through such pull the motion is transmitted to the transom, swinging it on its pivots. If the transom is not centrally pivoted and, therefore, not substantially balanced on its pivots, the motion of the transom, when permitted by operation of handle 32, would still merely result in tensioning one of the links 24 or 25. The arrangement of the lost motion connection between the upper ends of the links and the lever 23 is such that a thrust is not transmitted at any time through one of the links to the transom.

Although but one specific embodiment of this invention has been herein shown and described, it will be understood that details of the construction shown may be altered or omitted without departing from the spirit of this invention as defined by the following claims.

I claim:

1. A casement structure including a frame, said frame being hollow and including a vertically disposed channel bar for supporting operating mechanism, a bearing secured to the upper end of said channel bar, a window pivotally supported in said frame and carrying a shaft extending through said bearing,

a lever on said shaft, a support and housing for worm gearing secured to said channel bar and spaced downwardly from said bearing, worm gearing in said housing and including a worm wheel, a pair of links pivotally attached to said worm wheel at their lower ends and pivotally attached to said lever at their upper ends, and a handle for operating said worm gearing.

2. A casement structure including a frame, said frame being hollow and including a vertically disposed bar for supporting operating mechanism, a bearing secured to the upper end of said bar, a window pivotally supported in said frame and carrying a shaft extending through said bearing, a lever on said shaft, a support and housing for worm gearing secured to said bar and spaced downwardly from said bearing, worm gearing in said housing and including a worm wheel, a pair of links pivotally attached to said worm wheel at their lower ends and pivotally attached to said lever at their upper ends, said pivotal connections being arranged to provide for lost motion whereby each link transmits motion by pull only, and a handle for operating said worm gearing.

Signed at Chicago this 12th day of June, 1930.

FORREST C. GARRISON.
